UNITED STATES PATENT OFFICE.

JOSEPH STUBBERS, OF COVINGTON, KENTUCKY.

GAS-BURNER.

SPECIFICATION forming part of Letters Patent No. 586,748, dated July 20, 1897.

Application filed February 21, 1896. Serial No. 580,150. (No model.)

To all whom it may concern:

Be it known that I, JOSEPH STUBBERS, a citizen of the United States, residing at Covington, in the county of Kenton and State of Kentucky, have invented a certain new and useful Improvement in Gas-Burners, of which the following is a specification.

My invention relates to an improvement in burners for use in connection with either vapor or coal gas, and more especially to the vapor-gas burner (having an incandescent mantle) for which United States Letters Patent No. 538,801 were issued to me May 7, 1895; and it consists in the novel features of construction hereinafter fully described, and particularly pointed out in the claims.

In the accompanying drawings, Figure 1 is an elevation of my invention in its preferred form, showing the parts with the gas turned on full force and the air cut off entirely from the mixing or mingling chamber; Fig. 2, a central sectional elevation of the same, but omitting the glass chimney and its supports, and also showing an independently-operating form of air cut-off; and Fig. 3, a broken sectional plan on line $\alpha\alpha$ of Fig. 1.

A represents the burner-barrel, having the usual spider B for supporting the glass chimney C.

30 D is a conical Welsbach mantle supported over the burner-barrel by means of the customary standard or frame d.

a and a', respectively, represent the usual cup and perforated diffuser-cap set on the 35 top of the burner-barrel to lie within the encompassing lower end or mouth of the mantle D.

b represents an ordinary gas-tube forming the arm of a gas-fixture—such as a chandelier, 40 or pendant, or a wall-bracket—the end cap b' having the usual screw-threaded upturned nipple b'', which conveniently engages the internally-threaded lower end or mouth b' of the burner-barrel.

45 c is a transverse slot constructed in the burner-barrel slightly below the spider B, and c' is a sleeve or band sliding over said burner-barrel in connection with said slot c to control and regulate the entrance of atmospheric air therethrough.

E represents a disk or plug fitting rigidly within the burner-barrel on a plane with the

bottom of slot c and having an inwardly-tapering orifice e, as best seen in Fig. 2.

F represents a hollow vertically sliding or reciprocating plug-fitting, free from peripheral leakage, within the burner-barrel and having a conical needle-point valve f projecting upwardly therefrom to engage the orifice e in the stationary disk E. The plug F 55 is preferably bored centrally to form a main gas-passage f' part way up, and then small exit-holes or inclined branches f'' are made in its top, leading from the said central bore to the space above in the burner-barrel.

a² is a vertical slot in the burner-barrel through which projects a lateral pin or stud F', whose inner end is set firmly in the plug F.

G represents a cross-bar or lever pivoted to an arm or lug g, constructed on the burner-barrel adjacent the slot a², and G' G' are manipulating-chains attached to the outer ends of said lever. The outer end of stud F' engages a longitudinal slot or elongated opening g' in lever G, whereby the latter is operatively coupled to the plug F. I prefer to provide an expansion spring-washer II on the pivot h of the lever G, so that the latter shall be properly held in the desired position for the correspondingly proper holding of the 80 movable plug F in relation to the gas-orifice e within the burner-barrel.

I represents a link connecting the lever G with the valve-sleeve c', a lateral eye i being provided on the latter, to which the upper 85 end of the link is loosely attached. This link enables me to couple the air controlling-valve sleeve with the gas controlling-needle-valve plug, so that they shall act simultaneously and whereby the proper proportions 90 and admixture of air and gas are very readily accomplished and maintained at all times. The construction shown in Fig. 1 and the coupling of the air and gas controllers so that they shall act in harmony is provided for use 95 in connection with vapor-gas, where the quality thereof is variable; but when coal-gas is used in the service-pipe with a practically constant or even pressure and quality there is very seldom any need of a supply of air 100 through the side opening or slot c or any regulating thereof, so that I operate the gas-controller valve and air-controller sleeve independently by dispensing with the link and

simply setting the said controller-sleeve to shut off the air from the opening *c* entirely, as seen in Fig. 2, or arranging it anywhere else along or around the tube *A* in connection with the said opening *c* to suit the amount of air required, a set-screw *J* being used to secure it in position should the sleeve be a vertically-operating one.

In the operation of my burner, the lever 10 being in the position shown in Fig. 1, the gas flows in a full volume upward from the nipple into the sliding needle-base or hollow plug *F*; thence through the exit-holes *f*² therein to and through the orifice *e* in the stationary disk *E*, where its volume is controlled by the needle-valve *f*; thence into the upper chamber of the burner barrel or tube for combustion at its top diffuser *a'*. If the gas is too rich and a supply of air is therefore necessary, the chain to the right, Fig. 1, is simply drawn down, thus raising the needle-point valve (diminishing the volume of gas) and also simultaneously raising the valve-sleeve, the latter action permitting air to enter 25 through the side opening *c* in the burner-barrel immediately above the gas-orifice *e*, at which point they readily commingle, and the product passes upward to the combustion-cap at the top, where the heat generated causes 30 the mantle to become thoroughly incandescent and produce an intense and steady light for illumination.

It is very essential that the orifice through which gas passes just before it enters the combustion-chamber should be clear and free from any obstruction, so as to admit gas to pass therethrough with full force and thereby create a suction or siphoning of air. It will be readily seen that with my device I can 35 readily clean said orifice should it become clogged. Another feature is, viz: The pressure and quality even of artificial gas are different in different cities and sometimes in the same city. Now it is very essential to have 40 this opening exactly the proper size, so as to admit the proper amount of gas required to heat the mantle to a point of incandescence. When too much gas is used, it is not only a waste of gas, but it also shortens the life of the 45 mantle and diminishes its illuminating power. When the orifice admits too little gas, the illuminating power is greatly decreased. It will be readily seen that these difficulties are 50 obviated through my device, as the gas-opening can be readily adjusted so as to admit any desired quantity of gas and the open-bottom burners adapted to be attached to or screwed on any fixture. The features herein are at 55 once simple, readily adjusted, and operated.

I claim—

1. In a gas-burner, the combination, of an open-ended burner-barrel, the side of which is provided with a longitudinal and with a circumferential opening, a stationary orificed disk in the barrel between said openings, a 60 movable gas-orificed needle-pointed valve within the barrel below the disk, a handle in the valve projecting through the longitudinal opening in the barrel, and a band around the barrel at the circumferential opening, substantially as set forth.

2. A gas-burner composed of a burner barrel or tube having a valve-controlled air-inlet orifice therein; a stationary, gas-orificed disk or plug mounted in said barrel adjacent the 75 air-orifice; a movable, gas-orificed needle-pointed valve arranged within said barrel below said disk and adapted to engage the gas-orifice therein; a manipulating cross-bar or lever pivotally mounted on the burner-barrel 80 and having an opening therein engaging a stud or pin projecting laterally and outwardly, through an opening in the said barrel, from the base of the needle-point valve; and a link-coupling between said lever and 85 the air-controlling valve; the whole being constructed and adapted to operate so that the supply of gas and air to the burner is properly controlled and commingled, substantially as herein set forth.

3. A gas-burner composed of a burner-barrel having one or more air-orifices therein; a vertically-movable sleeve or band surrounding said barrel and controlling said air-orifices, and having means for securing it in the 95 desired position; a gas-orificed plug or disk rigidly mounted in said barrel adjacent said air orifice or orifices; a gas-orificed needle-point valve movably mounted within said barrel below said stationary disk and adapted to 100 engage the orifice therein; a manipulating cross-bar or lever pivotally mounted on the burner-barrel and having a frictional, expansion-washer mounted on its bearings; a stud or pin projecting outwardly, through a vertical slot in the barrel, from the needle-point valve, and engaging an elongated opening in 105 said manipulating-lever; the whole being constructed and adapted to be operated so that the air and gas inlet orifices are controlled, substantially as herein set forth.

In testimony of which invention I have hereunto set my hand,

JOSEPH STUBBERS.
